UNITED STATES PATENT OFFICE.

ALVA J. FISHER, OF EVANSTON, ILLINOIS, ASSIGNOR TO HURLEY MACHINE COMPANY, OF CHICAGO, ILLINOIS, A CORPORATION OF ILLINOIS.

VACUUM-CLEANER.

1,351,032.

Specification of Letters Patent. Patented Aug. 31, 1920.

Application filed December 18, 1916. Serial No. 136,802.

To all whom it may concern:

Be it known that I, ALVA J. FISHER, a citizen of the United States, residing at Evanston, in the county of Cook and State 5 of Illinois, have invented certain new and useful Improvements in Vacuum-Cleaners, of which the following is a specification.

My invention relates to a vacuum cleaner of that type provided with a suction nozzle and suction fan, operated preferably by an electric motor, through which fan the dust-laden air is drawn and forced into a separating receptacle such as the usual dust bag. My invention pertains more particularly to the construction of the casing for the fan and the casing for the suction nozzle as well as to other features such as the means for supporting the bearings for the forward rollers of the machine, and also to 15 means for mounting the longitudinal strip in the nozzle opening. The object of my invention is to provide a novel and efficient construction of vacuum cleaner particularly in the respects above noted.

25 In the accompanying drawing Figure 1 is a sectional elevation of a vacuum cleaner embodying my invention; Fig. 2 a vertical sectional elevation on the line 2—2 of Fig. 1; Fig. 3 an elevation of the lower portion 30 of the nozzle; Fig. 4 a detailed view of one end of the nozzle casing; Fig. 5 a detail section on the line 5—5 of Fig. 2, and Fig. 6 is a fragmentary elevation of the outlet side of the fan casing.

35 The vacuum cleaner structure comprises essentially three separate casings A, B, and C, all made of sheet metal formed and secured together in the manner hereinafter shown.

40 The nozzle casing A is formed of two separate sections, a front section a and a back section a' , which are substantially similarly shaped, but reversed, and joined together at a^2 by welding, thereby constituting an integral structure. The front section a is provided with an opening a^3 bordered by an integral flange a^{10} which is adapted to receive a suction hose when desired, but which is normally closed by the cap a^4 . The 45 back section a' is provided with a similar opening a^5 which establishes communication between this suction nozzle and the interior of the fan casing.

As shown in Figs. 4 and 5 the ends of the 50 sections a and a' are so restricted and

shaped as to together form at each end a vertical cylindrical chamber a^6 , which is adapted to receive a vertically movable bolt D, whose stem passes through the top of such chamber and is provided with an adjusting nut d , another nut d' being provided at the extreme end of the stem to prevent the removal of such bolt. The lower end d^2 of this stem is of plain cylindrical form and is slotted to receive the extended 60 end e of the transverse strip E, which is movable vertically in the nozzle opening and adapted to bear upon the surface to be cleaned. This cylindrical end d^2 of the bolt is secured somewhat loosely to this strip in 65 a suitable manner as by means of the rivet or pin e' .

The lower edge of the front section a is rolled outwardly and upwardly to form a horizontal tube a^7 , thereby providing a 70 bearing for the two rods F, whose ends projecting beyond the ends of this tube are bent upwardly and then horizontally to form the bearings f' for the forward rollers 75 G of the machine. These rods F are held 80 in the tube as the result of spot welding at f . The lower edge of the back section a' is rolled over in similar manner to form a tube a^8 , but merely to form a rounded surface for presentation to the article to be cleaned. 85

The casing B which incloses the fan (not shown) comprises two substantially similar sections b , b' , whose meeting edges are welded together at b^2 , thereby making a practically integral structure. The front 90 section b has a central opening similar to and communicating with the opening a^6 , and the edges of these openings are held together by means of a ring H which is preferably a flange formed on section a' , rolled 95 or spun over the edge of the opening in section b . The back section b' is closed as to its walls except for an opening for communication with the casing C that is to house the electric motor (not shown). The 100 casing B is provided with a suitable exhaust opening I, a portion thereof being on each section with the exception of extreme outer end of such exhaust opening, which is wholly on the section b' .

105 The nozzle casing A fits flush against the front wall of the fan casing B, the opening a^5 of course registering with the corresponding opening in the fan casing. When these two casings are thus brought together 110

in juxtaposition they are held together as an integral structure by welding, preferably by spot-welding, as shown at a^o . The motor case C is substantially cylindrical but 5 provided at its forward end with a circular marginal flange c, which is secured in suitable manner as by means of the screws c' to the rear wall of the fan casing B. This motor casing is provided with brackets C' in 10 whose lower ends is mounted the rear supporting wheel J.

According to this construction I am able 15 to dispense with castings usually of aluminum, and to employ with equal or better satisfaction thin plates of sheet steel, and yet be enabled to attain the proper shapes and configurations required by the nozzle and fan casing, including the exhaust opening thereof. Although two of the casings 20 are made in sections they are efficiently welded together to form a practically integral structure, besides which by welding the nozzle casing and fan casing are secured together as if they also were practically integrated. Moreover the structure described 25 provides a suitable bearing for the shaft or rod of the small wheels or rollers G.

I claim:

1. A vacuum cleaner structure comprising 30 a nozzle casing and a fan casing secured together, the former casing having a bottom nozzle opening whose front edge is rolled into a tube, a rod passing into such tube and supporting a roller on the end of the rod. 35

2. A vacuum cleaner structure comprising 40 a nozzle casing and a fan casing secured together, the former casing having a bottom nozzle opening whose front edge is rolled into a tube, rods received by such tube and having their ends bent upwardly and then horizontally, and supporting rollers on the extreme ends of the rods. 45

3. A vacuum cleaner structure comprising 50 a nozzle casing made of sheet metal in two substantially similar sections welded together, the ends of the nozzle casing being extended to form vertical cylindrical chambers, bolts vertically movable therein, and a strip longitudinally arranged in the nozzle opening and secured to the lower ends of said bolts.

ALVA J. FISHER.
